(57) **CLAIM**

The ornamental design for a cap, as shown and described.

DESCRIPTION

FIG. 1 is a perspective view showing the front and a side of a first embodiment of a cap;

FIG. 2 is a view of a rear side of the first embodiment of the cap;

FIG. 3 is a view of the front side of the first embodiment of the cap;

FIG. 4 is a view of the left side of the first embodiment of the cap;

FIG. 5 is a view of the right side of the first embodiment of the cap;

FIG. 6 is a plan view of the top of the first embodiment of the cap;

FIG. 7 is a view of the underside/interior of the first embodiment of the cap;

FIG. 8 is a perspective view showing the front and a side of a second embodiment of a cap;

FIG. 9 is a view of a rear side of the second embodiment of the cap;

FIG. 10 is a view of the front side of the second embodiment of the cap;

FIG. 11 is a view of the left side of the second embodiment of the cap;

FIG. 12 is a view of the right side of the second embodiment of the cap;

FIG. 13 is a plan view of the top of the second embodiment of the cap;

FIG. 14 is a view of the underside/interior of the second embodiment of the cap;

FIG. 15 is a perspective view showing the front and a side of a third embodiment of a cap;

FIG. 16 is a view of a rear side of the third embodiment of the cap;

FIG. 17 is a view of the front side of the third embodiment of the cap;

FIG. 18 is a view of the left side of the third embodiment of the cap;

FIG. 19 is a view of the right side of the third embodiment of the cap;

FIG. 20 is a plan view of the top of the third embodiment of the cap; and,

FIG. 21 is a view of the underside/interior of the third embodiment of the cap.

The broken lines in FIGS. 15-21 illustrate unclaimed portions of the article and form no part of the claimed design.

1 Claim, 9 Drawing Sheets
